UNITED STATES PATENT OFFICE

2,666,628

MINING MACHINE WITH SUPERPOSED
WEDGE-LIKE CUTTER

John Connel Sproul, Glasgow, Scotland, assignor to Mavor & Coulson, Limited, Glasgow, Scotland

Application February 25, 1950, Serial No. 146,181

3 Claims. (Cl. 262—8)

1

Machines for mining coal and other minerals have been previously proposed which have a head incorporating two or more superposed cutters arranged to strip off the mineral by a wedge-like action at different levels from a seam in the advance along it of the machine, the cutters having edges that are co-planar, or approximately so, in order that the cutters act along a plane behind and roughly parallel to the vertical face of the seam.

The present invention relates to machines as aforesaid but of a previously proposed type in which at least one cutter projecting in advance of the other or others so as, in effect, to plough out from the face a deep furrow, leaving the other cutter or cutters the now facilitated task of stripping off the coal or other mineral left outstanding above and (or) below the furrow. For instance, in one previously proposed construction of machines of this type, there are three superposed cutters; and it is the intermediate cutter that projects well in advance of the cutters above and below it so as to plough out from the face a furrow at an intermediate level.

In coal seams it is sometimes found that the coal at different levels has different characteristics. For instance, there might be a layer of coal which is softer than the coal above and (or) below it. There are circumstances under which it is desirable to plough out the advance furrow at the level of this layer. Some characteristic other than softness might render a layer appropriate for advance cutting.

Therefore, according to this invention, in a mining machine of the type stated two or more superposed cutters are mounted on a supporting head in such a manner as to be detachable, removable and interchangeable, so that the forwardly projecting cutter can be set at a selected level considered most appropriate to the nature of the coal or other mineral seam.

A machine of the before-mentioned type, designed for mining coal, is shown by way of example in the accompanying drawings to illustrate the invention. In the drawings, Figs. 1 and 2 are a diagrammatic side elevation and a plan of the machine. Fig. 3 is a side elevation of the cutter head, drawn to a larger scale, the view being partly in section approximately on the line 3—3 of Fig. 4. Fig. 4 is a corresponding plan of the cutter head, this view being partly in section on the line 4 of Fig. 3. Fig. 5 is a fragmentary section drawn to a still larger scale approximately on the line 5—5 of Fig. 4. Fig. 6 is a sec-

2

tional elevation corresponding to Fig. 5, the section being on the line 6—6 of Fig. 1.

The general arrangement of the mining machine to which the invention is shown applied is drawn in simple outline in Figs. 1 and 2, the construction and operation of the machine in general not being material to the present invention. In order that the relationship of the invention to the machine can be adequately understood, the following brief description of the machine is given.

The machine shown is double-ended, comprising mainly a frame like body 7, 8, 9 and 10, a carriage 11 and two cutter heads 12 and 13. The body consists of two transverse end walls 7 and 8, to which the heads are connected, and two longitudinal guide bars 9 and 10, on which the carriage is slidably mounted.

The carriage incorporates hydraulic propulsion apparatus. This apparatus includes a vertical hydraulic jack consisting of a cylinder 14 with a foot 15, the cylinder being vertically movable in a holder 16 incorporated in the carriage, and a piston-operated head 17 which normally rests upon the holder. The propulsion apparatus also includes a hydraulic ram unit consisting of a horizontal cylinder 18 and a ram 19 extending from both ends of the cylinder and engageable at its ends with the walls 7 and 8.

In order that the machine shall be propelled say from left to right (as viewed in Figs. 1 and 2), the jack is operated firstly to depress its foot 15 against the floor of the mine and secondly to lift its head 17 against the mine roof. The jack thus extended provides a securely anchored abutment. Next the ram unit is operated so that the ram 19 is forced to the right, the ram thus engaging the wall 8 and pushing the framewise body 7—10, with the head 13 leading, upon the mine floor towards the right, the guide bars 9, 10 sliding through the now stationary carriage 11. Thus, the head 13 performs its cutting stroke. Thereafter, the jack is operated so that its head is lowered and its foot raised, thus contracting the jack and freeing it from the roof and floor. Finally, the ram unit is operated so that the ram 19 is forced to the left, the ram thus engaging the rear wall 7 and pushing the carriage 11 so that it freely slides to the right hand end of the guide bars 9, 10 to take up a new position of anchorage for the next cutting stroke. This completes the cycle of operations.

Both cutter heads 12 and 13 are of similar construction. Therefore only one of the heads,

namely the right hand head 13, is hereinafter described.

In the example, the cutter head comprises a leading cutter 20 at an intermediate level, two cutters 21 and 22 above the cutter 20, a floor cutter 23 and a roof cutter 24. The cutters 20-24 have edges 20A-24A all nearly in the same vertical plane A, Figs. 2 and 4. The floor and roof cutters also have horizontal edges 23B, 24B. The floor cutter is associated with a sloping ramp 23C for lifting the coal from the floor and deflecting it sidewise from the path of the machine for conveyance from the mine workings.

Referring also to Figs. 3 to 6, each of the main cutters 20, 21, 22 and 23 is an edged plate that is attached to an approximately wedge-like body, the bodies being indicated by 25, 26, 27 and 28 respectively. It will be noted that the body 25 of the intermediate cutter 20 is considerably longer than the bodies 26, 27 and 28, so that the cutter 20 projects well in front of the others. The cutter head includes a heavy casing 29 in which the bodies 25-28 are all pivotally mounted. The casing 29 is formed with a base shelf 29A, a top shelf 29B and intermediate shelves 29C, which divide the casing interior into compartments each accommodating one of the cutter bodies. The casing 29 is attached by a connector 30 to the adjacent end wall 8 of the framewise body 7-10 of the machine.

Each of the four cutter bodies is in the nature of a lever with a central bearing boss, the several bosses being indicated by 25A, 26A, 27A and 28A respectively. From each boss there extends an arm 25B, 26B, 27B or 28B of the lever concerned. Each of these arms is in the form of an interconnected pair of upper and lower cheeks, and all of these cheeks have terminal eyepieces 25C-28C, which bear against vertical-thrust plugs 41 fitted into the shelves 29A-29C. These plugs 41, as Figs. 3 and 5 show, each consist of a cylindrical body, which fits firmly into a hole in the shelf above or below the plug, and of a flange which serves as a slide-bearing surface for the associated cutter-lever boss 25C, 26C, 27C or 28C. The fulcrum of the four lever-like bodies 25-28 is a four-part pivot pin 31, the parts of which fit slidably through the bosses 25A to 28A and also through co-axial bearings 32 in the casing shelves 29A-29C. The lowermost part of the pin 31 is supported by a cross-pin 31A.

The cutter bodies are made like levers in order that they can be pivotally adjusted so as to vary the setting of the cutters 20-24 individually in relation to the supporting casing 29. Therefore each cutter body has adjustment means. In the example, the means provided for each body comprises the following components:

A turnable screw 33 which is journalled in a bracket 33A on one of four covers 34 that are bolted to the casing 29 and form a closure to the front side of the compartments thereof;

A nut 35 which is slidable along a horizontal inner slideway 36 in the associated cover and through which ordinarily the screw 33 is threaded;

A link 37 pivotally connected at its opposite ends by a pin 38 to the associated nut 35 and by a pin 39 to the eyepiece of the associated lever arm 25B, 26B, 27B or 28B.

In order to adjust any of the cutters laterally, the associated screw 33 is turned appropriately, say by means of a ratchet-lever, or a spanner, engageable with a square head 40 on the screw, this head extending from the casing 29. Such

turning of the screw causes the nut 35 to move along its slideway 36 and the link 37 to move angularly in the manner of a toggle-link, so that the cutter is forced to change its angular relationship to the casing 29.

In order to interchange any two of the cutter bodies 25, 26 and 27, the pivot pin 31 is withdrawn upwards part by part so far as necessary. The appropriate two screws 33 are unscrewed from their nuts 35 and these nuts are slid from their slideways 36. The two associated covers 34 are unbolted and removed, together with their screws 33. Thus, in each of the two compartments whose covers have been removed, the following components lie exposed, namely the nut 35, its link 37 and the cutter-lever arm 25B or 26B or 27B or 28B, as the case may be, all of said components being freely withdrawable as an assembly from their compartments. Accordingly, each of the two cutter bodies to be interchanged and the associated assembly of components 35, 37, 38 and 39 are removed from the cutter head. During removal, the pins 39 concerned each slide freely between and away from the vertical-thrust plugs 41 fitted in the shelves above and below, each of said pins remaining as the pivotal connection between its link 37 and cutter-lever arm. Thereafter, the cutter bodies with the parts connected to them are re-inserted in their new positions, and the previously withdrawn parts of the pivot pin 31, the covers 34 and the nuts 35 are re-positioned.

Patent application No. 146,182 of the same date as the present application shows and describes as in the present application the same as is shown and described in the present application but claims an invention that is different from the invention hereinafter claimed.

I claim:

1. A mining machine of the type stated having a cutter-supporting head, a plurality of shelves incorporated in said head, said shelves being vertically spaced apart to provide compartments, a plurality of superposed cutters mounted on said shelves, there being one cutter in each inter-shelf compartment, and said cutters including one which projects prominently forwards, and a withdrawable plural-part pin attaching the cutters to the head, the pin parts each extending between two of said shelves and said pin parts being withdrawable so that two of the cutters can be detached, removed from the head, interchanged and again attached to the head by re-insertion of the withdrawn pin parts.

2. A mining machine as claimed by claim 1 in which the cutters incorporate lever-like bodies which are fulcrumed on the plural-part pin, and in which mechanisms associated with said bodies, respectively, connect the associated bodies to the head, each of said mechanisms being operable to adjust the associated cutter body laterally in relation to the head and said mechanisms including interchangeable components which are detachable and attachable with the bodies.

3. A mining machine of the type stated having a cutter-supporting head, a plurality of superposed cutters pivotally mounted on said head so as to be laterally movable in relation thereto, supports whereby said head is divided at different levels, a plurality of superposed co-axial pivot pins attaching the individual cutters to said supports, and manually adjustable superposed means for adjusting the cutters laterally about their pivot pins, there being one of said pivot pins and one of said adjustable means for each cutter at

2,666,628

5

the level of said cutter and said pivot pins and
adjustable means being removable so that the
cutters are detachable from the head and inter-
changeable in order that each cutter can be
mounted at a selected level on said head.

JOHN CONNEL SPROUL.
